UNITED STATES PATENT OFFICE.

ANNIE P. ATKINSON, OF GULFPORT, MISSISSIPPI.

BED ATTACHMENT.

1,066,976.

Specification of Letters Patent.

Patented July 8, 1913.

Application filed September 16, 1912. Serial No. 720,643.

To all whom it may concern:

Be it known that I, ANNIE P. ATKINSON, a citizen of the United States, residing at Gulfport, in the county of Harrison, State of Mississippi, have invented certain new and useful Improvements in Bed Attachments; and I do hereby declare the following to be a full, clear, and exact description of the invention, such as will enable others skilled in the art to which it appertains to make and use the same.

This invention relates to novel and useful improvements in bed attachments and the invention consists in providing a safety attachment to prevent the occupant of the bed from falling out thereof, though the device is especially adapted for children's use.

Another object of the invention is to provide an improved, simple and novel form of attachment which may be applied to beds of various types and which is so constructed as to be readily adjusted to a spring and fitted beneath the mattress whereby it may be supported in an upright position at the side of the mattress or folded beneath the mattress without withdrawing it, and when so disposed prevents sagging of the central portions of the bed spring.

With the above and other objects in view, the invention consists of certain combinations and arrangements of parts as will be hereinafter more fully described, claimed and illustrated in the accompanying drawings, in which:

Figure 1 is a side elevation of a bed with my improved attachment applied thereto. Fig. 2 is a cross sectional view taken on the line 2—2 of Fig. 1. Fig. 3 is a detail perspective view of the attachment removed. Fig. 4 is a view similar to Fig. 2 but showing only a fragmentary portion of the bed and with the device folded.

In illustrating the embodiment of the invention, there is indicated a bed, the head posts 10 and the foot posts 11 of which are connected by the usual side rails or boards 12. A mattress spring 13 of the usual fabric type is supported on the side rails and a mattress 14 rests on the spring in the usual manner.

The attachment comprises a pair of hinged sections or slabs comprising an open frame 15 relatively long and narrow and connected by diagonal brace wires 16, said frame being fitted between the mattress and the

spring as shown. A pair of hooks 17 are slidably mounted or freely movable on the inner side of the frame 15 and the hooks extend downwardly to be engaged in the spring for securing the frame against movement. It will also be apparent that by having the hooks movable on the frame, they can be adjusted to suit the various types of springs. The other open frame is indicated by the numeral 18 and is disposed in an upright position at one side of the mattress and is connected at closely related and equidistant points by vertical guard wires 19 which serve to give or flex outwardly to avoid injury to the occupant of the bed but effectually prevent falling out of the bed. This structure also affords plenty of sleeping room for children owing to the fact that they can sleep in contact with the upright frame without being caught therein or injured. These two frames are hinged together at two points as shown at 20, the butts of the hinges being so formed as to limit the spreading of the leaves through the medium of shoulders 21 whereby the upright frame can swing against the horizontal frame by raising the side of the mattress but will be held against outward displacement beyond a vertical or upright position.

The special advantages of this structure are its simplicity and lightness and also the fact that it can be folded beneath the mattress without the necessity of removing it from the bed and besides occupying but little room, it will be out of the way when not in use and will effectually prevent sagging of the spring to some extent.

I claim—

1. A safety attachment for beds embodying two rectangular frames hinged together and means to limit the movement of one frame to an upright position when the other frame is disposed beneath the mattress.

2. A safety attachment for beds and the like embodying hinged frames, said hinges preventing outward movement of one frame disposed in an upright position at one side of a bed while the other frame is horizontally disposed and means for engaging a spring to hold the last mentioned frame against movement.

3. An attachment for beds embodying two open frames, hooks longitudinally movable on the free side of one frame to engage vari-

ous types of springs and beneath the mat-
tress of a bed, means pivotally connecting
the frames to limit the movement of the
other frame at right angles to the first men-
tioned frame carrying the hooks and guard
wires for the last mentioned frame.

In testimony whereof, I affix my signa-
ture, in presence of two witnesses.

ANNIE P. ATKINSON.
